UNITED STATES PATENT OFFICE.

SAMUEL E. TOMPKINS, OF NEWARK, NEW JERSEY.

HARNESS-SADDLE.

SPECIFICATION forming part of Letters Patent No. 286,347, dated October 9, 1883.

Application filed December 8, 1882. (No model.)

To all whom it may concern:

Be it known that I, SAMUEL E. TOMPKINS, a citizen of the United States, residing at Newark, in the county of Essex and State of New Jersey, have invented certain new and useful improvements in Saddles; and I do hereby declare the following to be a full, clear, and exact description of the invention, such as will enable others skilled in the art to which it applies to make and use the same, reference being had to the accompanying drawings, and to letters of reference marked thereon, which form a part of this specification.

The object of this invention is to produce a first-class "hand-made" pad for coach-harness, which will be cheap, and yet retain the upper metallic pad-plate between the top-leather and the lining-leather, as found in the pads heretofore in use, usually denominated "hand-made" pads.

The invention consists in the arrangements and combinations of parts, substantially as herein set forth and shown.

Referring to the accompanying drawings, embodied in two sheets, in which similar letters of reference indicate like parts in each of the several figures, Figure 1 is a plan view of a half-section of a saddle embodying my improvements; Fig. 2, a sectional view of a portion of the same, the section being taken through line *x* of Fig. 1; Fig. 3, a detail view of a portion of a lower plate; and Fig. 4, a section of the same, taken through line *w* of Fig. 3. Fig. 5 shows plan and sectional views of an improved pad-screw nut adapted to engage with the before-mentioned lower plate, and Fig. 6 is a plan of a portion of the upper or main plate. Fig. 7 is a plan of the lower plate, or a half portion thereof, showing certain peculiarly-formed portions of leather fastened thereto; and Fig. 8 is a sectional view of the same, taken through line *y* of Fig. 7. Fig. 9 is a side view of a metallic fastener adapted to engage with the before-mentioned nut and lower plate. Fig. 10 illustrates a method of forming the lower plate into two parts and securing said parts together, adapting said plate to certain conditions. Fig. 11 is an end view of one of said parts, showing more clearly the manner of forming certain projecting lugs thereon; and Fig. 12 is a detail view of the lower plate, showing my peculiar methods of

constructing the same, whereby it is adapted to receive certain adjustable pad screw and terret nuts.

In constructing my improved pad I form the plate *b*, which I insert in the top, as before described, to which the pad-hook *v* can be firmly secured without its being necessary to cover the nut which fastens the said pad-hook with a piece of leather to hide it, as done in the said imitation hand-made pads. The top plate, *b*, has secured upon it the leather top piece, *a*, the edges of which are sewed or otherwise secured to the leather lining-strips *d*, which extend beneath the plate, as shown in Fig. 2. The inner edges of the said strips *d* may be united by being stitched, inclosing the plate, as will be readily understood.

Beneath the parts thus described is arranged an under plate, *f*, made concavo-convex, (the concavity being on the upper side,) with upwardly-curved strips *e*, of leather, secured to the edges. The edges of the concavo-convex under plate force the strips *e* against the lining *d* when the parts are brought together by the terrets and pad-screws. Said strips *e*, curving upward upon each side of the upper portions, *a b c d*, and engaging with the pad bottom-leather *h*, are bound together with said bottom-leather, as shown in Fig. 2, the binding-strip being lettered *h'*. The under plate, *f*, has tack-holes *k* along its margins, for the purpose of tacking on the upwardly-curved strips *e*, *m*, Fig. 7, indicating the ends of the tacks as they appear clinched in the leather.

On the ends of the under plate, *f*, and neatly engaging with the extremities of the strips *e*, are fastened the end pieces, *n*, as shown in Fig. 7. The lateral edges of said pieces *n* are curved to correspond with the curved strips *e*, receiving the under leather, *h*, and the binding *h'*, as will be readily understood. The metallic plate *f*, the side strips, *e*, and end piece, *n*, form a socket-piece corresponding in a degree to the socket-pieces heretofore made from leather alone. My improved socket-piece, however, cannot shrink and warp, the metal under plates preventing such action, as will be evident.

It has heretofore been very difficult to make a hand-made coach-pad so that the mountings can be put in after the pad is made, and yet retain the upper or main plate, *b*, in the top.

To enable an experienced workman to perform these operations in a neat and substantial manner, whereby the cost of a pad is materially reduced, I form upon the concavo-convex 5 plate *f* raised bridges *o* for the terrets and pad-screw nuts *p*. Said nuts are secured to the bridges *o*, as shown in Fig. 7, by thin metallic fasteners *r*, which have an **I**, as shown in Fig. 9. Slots are formed in both the bridge *o* and 10 nuts *p*, into which the said fasteners *r* are secured by bending the free ends thereof, as shown in Figs. 7 and 9, thus holding the pad-screw nut or terret nut into intimate union with the bridge without the aid of the terret 15 or pad-screw, and yet allowing the nut to be drawn from beneath the bridge by simply removing the fasteners. Said fasteners *r* may be readily removed from the slots by bending up the free ends thereof, as will be readily understood. 20

When using thin leather in the construction of a cheaper grade of pad, it becomes necessary, from want of room, to sink the bridge *o*, as shown in Figs. 3 and 4. In this case I form 25 a raised bridge, *s*, and an end socket, *t*, set the nut into the perforated bridge, and then slide a thin plate, *u*, beneath the bridge *s*, across the nut *p*, and into the socket *t*, thus holding the nut firmly into position, but allowing the 30 latter to be readily removed and be replaced by another when the mountings are changed. It will be understood that said plate *u* is perforated, whereby the shank of the terret is allowed to pass into the nut beneath, and when 35 the terrets are screwed up it binds the nut, terret, and portions *s* and *t* into firm combination.

Under certain circumstances it may become difficult to cast the under plate, *f*, thin enough 40 in one piece. In such a case I cast the same in two or more pieces, forming ears or projecting lugs *a' a' a''*, Fig. 10, on the end of one piece, *a' a'* projecting from the upper edge, and *a''* from the under, so that the edge of the 45 opposite piece, *f'*, Fig. 10, will lie between.

Perforations are formed in the lugs *a' a''* and in the adjacent piece *f'*, which enable the two plates to be tacked or riveted together.

Under certain circumstances it may be necessary to form the raised bridge *o* for the terret, and the sunken bridge *o'*, with its accessory parts *s* and *t*, all in one plate, *f*. This may readily be accomplished, as shown in Fig. 12.

I am aware that, broadly, raised bridges 55 upon a saddle-tree are not new, and also that concaved trees have been used, and therefore these features I do not wish to be understood as claiming, broadly.

Having thus described my invention, what I claim, and desire to secure by Letters Patent, 60 is—

1. In combination, in a harness-saddle, the concave metallic under plate, the upwardly-curved strip of leather *e*, and the end piece, *n*, having curved lateral edges, the whole 65 forming a socketed under portion of a saddle, adapted to receive the upper portion thereof, *a b c*, substantially as herein set forth and shown.

2. In combination, the concave metallic 70 plate *f*, strips *e*, pad bottom-leather *h*, and the binding *h'*, uniting said strip *e* and bottom-leather, said parts combining to form a pad-socket, substantially as and for the purposes set forth.

3. In combination, the concave plate *f*, upwardly-turned strips of leather *e*, secured to the lateral edges thereof, and the bottom-leather *h*, united to the strip *e* at its upper edge, substantially as herein set forth. 80

4. In combination, the notched bridge *o*, the notched pad-screw, and the fasteners having the shape shown, the free ends of which are capable of being bent in opposite directions to fasten the parts together. 85

5. In combination, the plate *f*, having perforated lugs or projections *a' a' a''*, and the perforated plate *f'*, all constructed and arranged as herein set forth and shown.

6. The plate *f*, having the notched and elevated bridge *o*, in combination with a pad-screw nut having the notches therein, and the fasteners, all arranged and operating substantially as herein set forth. 90

7. The pad-screw or terret nut herein shown 95 and described, having slots at each end, adapting said nut to be riveted to plates above or beneath, having perforations at varying distances apart.

8. In combination, in a saddle, an under 100 plate, *f*, a leather portion, *e*, secured to the said under plate and projecting upwardly therefrom, a bottom-leather, *h*, the edges of which coincide with the upwardly-turned leather *e*, and a binding portion securing the 105 edges of said portions *e* and *h* together, the whole forming a socketed pad for the reception of upper portions of the saddle, substantially as herein set forth and shown.

In testimony that I claim the foregoing I have hereunto set my hand this 22d day of November, 1882.

SAML. E. TOMPKINS.
